UNITED STATES PATENT OFFICE.

CHARLES C. PEARSON, OF HUNTSVILLE, ALABAMA.

PANTALOON GARMENT.

SPECIFICATION forming part of Letters Patent No. 281,790, dated July 24, 1883.

Application filed August 24, 1882. (No model.)

To all whom it may concern:

Be it known that I, CHARLES CHARLEY PEARSON, a citizen of the United States, residing at Huntsville, in the county of Madison and State of Alabama, have invented certain new and useful Improvements in Pantaloons Garments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to garments usually worn by gentlemen, and refers particularly to drawers and pantaloons for miners and others.

The object of my invention is to promote comfort to the wearer and durability to the garment; and it consists of the front and rear portions, constructed as shown and described, and a re-enforcing strip, all combined to form a garment, as hereinafter more fully described, and particularly pointed out in the claim.

20 25 In the accompanying drawings, Figure 1 is a perspective view of a pair of drawers, showing the location of the gathers or folds. In Fig. 2 the front is thrown open, showing the re-enforcing strip. Fig. 3 is a back view, and

30 Fig. 4 is a detail, showing the re-enforcing strips lapping. Fig. 5 is a view of the rear portion of a leg spread out, the dotted lines indicating the position of the notches or gathers to be formed therein. Fig. 6 is a view of the front portion of a leg spread out.

35 Like letters of reference indicate like parts in each of the figures.

A represents the front portion, and B the back portion, of a pair of drawers.

40 45 To provide a fullness in the cloth between the side seams and the back seam, there are two series of gathers or folds in the cloth at the points *c d* on each side. For a like purpose, there are two series of gathers, *e e*, (one on each side,) at the knee of each leg.

The pattern is made longer at the seams, in order to be folded, to provide for the taking

up of the cloth by the gathers. By means of these gathers a close fit can be made, while at the same time the cloth is relieved from strain at those points, which receive it to a great extent in a garment that approximates a close fit.

50 The back seam having the gathers *d* is covered by a re-enforcing strip, C, which not only strengthens the seam and cloth, but partially or wholly covers the gathers, which would otherwise be liable to chafe the wearer. The lower end of this strip laps the lower ends of the downwardly-projecting face-pieces of the 60 waistband, whereby greater durability is secured.

55 In lieu of gathers, V-shaped notches can be cut in the cloth, and the edges brought together and suitably secured; or the cloth can be simply folded.

A garment containing my improvements can be made to give a close fit, and at the same time permit all necessary flexions of the parts with ease and comfort to the wearer, and without strain or damage to the garment.

70 I am aware that men's drawers have heretofore been made with gathers in the front piece at the knee, and with a strip or notch cut out of the back portion at the knee, and therefore do not broadly claim such as my invention.

75 Having thus described my invention, what I claim as my invention, and desire to secure by Letters Patent, is—

80 As a new article of manufacture, a garment substantially such as herein shown and described, consisting of the front and back portions cut in the form shown, and having two series of gathers on each side seam of the back portion, two series of gathers at the knee in 85 the front portion, and a re-enforcing strip over the back seam, as and for the purpose set forth.

In testimony whereof I affix my signature in presence of two witnesses.

CHARLES CHARLEY PEARSON.

Witnesses:

CHAS. R. PICKARD,
JAS. A. B. LOVETT.
